(57) **CLAIM**

The ornamental design for a longboard wheel, as shown and described.

DESCRIPTION

FIG. 1 is an upper perspective view of a first embodiment of a longboard wheel, illustrating the wheels attached to an exemplary longboard;

FIG. 2 is an upper perspective view of the longboard wheel shown in FIG. 1;

FIG. 3 is a front view of the longboard wheel shown in FIG. 1;

FIG. 4 is a rear view of the longboard wheel shown in FIG. 1; FIG. 5 is a left side view of the longboard wheel shown in FIG. 1;

FIG. 6 is a right side view of the longboard wheel shown in FIG. 1;

FIG. 7 is an upper perspective view of another embodiment of a longboard wheel;

FIG. 8 is a front view of the longboard wheel shown in FIG. 7;

FIG. 9 is a rear view of the longboard wheel shown in FIG. 7; FIG. 10 is a left side view of the longboard wheel shown in FIG. 7; and,

FIG. 11 is a right side view of the longboard wheel shown in FIG. 7.

The broken lines shown are included for the purpose of illustrating the environment in which the article resides and forms no part of the claimed design.
